UNITED STATES PATENT OFFICE.

CHARLES STERN, OF JERSEY CITY, NEW JERSEY, AND RICHARD W. BRADEN, OF NEW YORK, N. Y., ASSIGNEES TO B & S MANUFACTURING PRODUCTS CORPORATION, OF JERSEY CITY, NEW JERSEY, A CORPORATION OF NEW JERSEY.

ATTACHMENT FOR LOCOMOTIVES.

Original application filed August 8, 1921, Serial No. 490,605. Divided and this application filed June 7, 1923. Serial No. 644,032.

The present invention relates to improvements in attachments for locomotives and is a division of our similarly-entitled copending application Serial No. 490,605 filed

August 8, 1921.

It is an object of the invention to provide an improved device, for effectively lubricating the cylinders of a locomotive, and at the same time serving to break the vacuum in the cylinders while the locomotive is drifting or coasting with the throttle closed.

No small trouble and annoyance has been experienced heretofore in the proper lubrication of the internal parts of locomotive cylinders and faulty lubrication has resulted in the frequent necessity for renewing piston rings, removing carbon, and otherwise repairing the pistons and scored cylinder walls. Moreover, it is desirable to insure the flow of lubricant not only when the engine is operating under steam, but also when drifting or coasting with the throttle closed.

It is another object of the present invention to accomplish the accurate and timely lubrication of locomotive cylinders by a device which will at the same time operate to relieve the vacuum which the traveling pistons tend to create in the cylinders when the engine is coasting or drifting, and which will furthermore serve to furnish lubricant to the internal parts whenever the locomotive is in motion without regard to whether it be drifting or moving under steam.

A further object of the invention is to provide a device for carrying out the above described purposes in a simple yet faithful manner, and wherein the device is of a simple and inexpensive structure and is so built up as to be capable of installation upon locomotives of present types without any material alteration therein.

A still further object of the invention is to provide means so that steam will cushion the steam pistons and their reciprocating parts in the steam cylinders and keep the superheated units moist while the locomotive is coasting or drifting.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a diagrammatic view showing the improved device connected to a locomotive valve chest.

Figure 2 is a vertical section taken through the device.

Figure 3 is a similar view showing a subsequent position of the parts.

Figure 4 is an elevation of the device with a portion shown in section.

Figure 5 is a vertical section of a lubricating attachment, and

Figure 6 is a longitudinal sectional view of a governing valve.

Referring more particularly to the drawings, in Figure 1, 66 designates in diagram the cylinder of a locomotive and 65 represents the valve chest. The numeral 100 designates the improved device which receives lubricant from a reservoir or tank 71 held on the locomotive at a higher level, communication being established by means of a sloping pipe 70.

The device 100 is also in connection with a source of steam supply at boiler pressure through a connection 95 and the device connects with the valve chest 65 by a pipe 2.

A lubricating cup is shown at 99 above the device 100 to supply the necessary oil to properly grease the various working parts within.

Referring to Figures 2, 3 and 4, the casing 100 is provided with the annular steam chamber 101 surrounding a central barrel 102 in which the stem 103 reciprocates vertically. A threaded connection 104 is made at one side of the casing for the connection of the steam pipe 95 which thus serves to connect the steam chamber 101 with the steam dome of the locomotive or other source of saturated steam supply. For instance, the connection 104 may receive the pipe 95 as shown in Figure 1 and the pipe 70, as shown in Figure 1, may be connected to the threaded boss 105 of the casing 100, there being an oil passage 106, leading downwardly at an inclination centrally of the casing and through the wall of the barrel 102, where such oil passage communicates with an annular cut-out portion 107 of the stem 103. A series of centrally in-

clined ports 108 set up a free communication between the cut-out portion 107 and the bore 109 of the stem. The lower portion of the stem is provided with a piston 110 operating in a cylinder 111 formed within the casing and axially thereof, with a passage 112 extending at the side thereof and below the same. The lower end of the casing is provided with a threaded part 113 to take a pipe such as the pipe 2 in Figure 1 which leads to the steam chest 65. The steam in the steam chest and channel 112 communicates with the bottom portion of the piston 110. Steam is also admitted to the upper side of the piston 110 by narrow ports 114. The stem is provided with an enlarged portion 115 which as shown in Figure 3 is adapted to close the communication between the steam chamber 101 and the channel 112. The lower end of the steam or the piston 110 carries an oil pipe 116 threaded removably into such stem or piston, and also being threaded at its lower end to receive a cap 117 provided with numerous small perforations 118 to allow of the descent of oil therethrough. Above, the stem 103 carries a piston 119 operating in a cylinder 120. The piston 119 and cylinder 120 are larger in diameter than the piston 110 and its cylinder 111, and the parts 121 which place the lower side of the piston 119 in communication with the steam chamber 101 are of larger diameter than the ports 114 of the lower cylinder 111. The head is composed of two sections 122 and 123 having flanges with a packing 124 therebetween and bolts 125 put through the flanges and packing to hold the head sections tightened together. The port 126 allows of the outlet of steam from the head when the upper piston 119 is in the lower position shown in Figure 2. As more particularly shown in Figure 4 a port 127 is provided in the lower portion of the lower cylinder 111 and communicates with a passage 128 in the casing, which leads upwardly to and communicates with the head. The flow of steam upwardly through this passage 128 is controlled by a spring-pressed check valve 129. A plug 130 at the lower end of the passage 128 may be removed for purposes of cleaning. The stem 103 is provided with a hollow projecting stem portion 131 which passes upwardly through the head and may with advantage be equipped with a supplementary lubricator as constructed according to Figure 5. In this instance, the extension stem 131 is screw-threaded at its upper end to receive the threads upon the boss 132 of the lubricating cup or reservoir 133 which is of a suitable capacity to contain a desired quantity of oil or other suitable lubricant. The oil is put in a plug 134 and regulated in its passage down through the extension stem by

the use of a needle valve 135 having a screw-threaded adjustment and being operable by a milled head 136. A by-pass 137 is provided about the containing portion of the lubricator and communicates both with the extension stem and with the space above the lubricant.

The steam is of course admitted freely to the bore 109 of the stem 103, such steam ascending through the perforations 118 of the cap 117. The steam ascends through the steam extension 131 and going about the by-pass 137, gets above the body of lubricant in the container 133 and equalizes the pressure above and below the same. The lubricant may therefore freely flow out as controlled only by the needle valve 35. This device is in the nature of an auxiliary lubricator.

Referring now more particularly to Fig. 6. In this instance the exhaust passage 126, which leads from the head 19, is shown to be placed in communication by a suitable pipe 73 or other desired connections with a tube 74 having a perforation 75 in alignment with the pipe 73 and with a socket 76 in which the pipe 73 may be screw threaded. A like perforation 77 is provided in the opposite side of the tube 74 and communicates directly with the outside atmosphere. These passages are adapted to be placed in communication by means of an annular channel 78 extending about the central portion of a cylindrical solid valve 79 which reciprocates in the tube 74 and is provided with stems 80 and 81 which project outwardly through the screw threaded and flanged heads 82 and 83 which close the opposite ends of the tube 74.

Coil springs 84 and 85 are disposed within the tube and engage at their outer ends the heads 82 and 83 and at their inner ends the opposite ends of the cylindrical valve body 79. The springs 84 and 85 are of a like strength and if left to themselves will bring the intermediate channel 78 to a central position where the ports 75 and 77 may align.

A bell 87 is mounted upon the end of the stem. In traveling, air induced by the movement of the locomotive will strike the bell 87 and will shift the valve body 79 rearwards so that its solid portion will come between the ports 75 and 77. Springs 84 and 85 are of a light character to permit this action when the locomotive is moving at a slow rate. Of course the area of the bell in conjunction with the strength of the springs will regulate the opening of the ports.

The operation of the device is as follows:—

Oil flows from the lubricating reservoir 71 down through the pipe 70 and into the passage 106. In either position of the valve 130

as shown in Figs. 2 and 3, the oil will be permitted to enter the cut-out part 107 and getting into the ports 108 will enter the bore 109 of the stem 103. It will be understood that an emergency oil is supplied also from the lubricator 133 at the top of the extension stem as heretofore described. The needle valve 135 is locked in place in adjustment by a nut as shown in Fig. 5. This supplementary or auxiliary oil is deemed desirable to lubricate the cylinder and steam chest while the engine is drifting or being towed, or if the other lubricating means should get out of order.

From the chamber 101, steam will flow upwards through the ducts 121 and downwards through the ducts 114, the chamber 101 being normally filled with steam. The piston 119 will have a large surface area presented to the steam as compared with the piston 110, and the ducts 121 are larger than the ducts 114. The result will be a quicker rush of steam beneath the piston 119 than down upon the piston 110, and the upper piston will thereby tend to move upwards and to be held against descent because of its larger area. This arrangement obviates the need of using a governor to close off the steam ports.

During the normal running of the locomotive with the throttle open the pistons 119 and 110 will remain in the upper position as shown in Figure 3, not only because of the presence of saturated steam beneath the upper piston 119 as just explained, but also because the lower portion of the lower piston 110 is subject to the steam chest pressure. In this raised position of the parts, the lower piston 110 exposes the port 127, as shown in Figure 4, to the steam within the lower cylinder 111 and this steam passes up through the passage 128, raises the non-return check valve 129 and enters the large chamber at the top above the piston 119. The steam accumulates in this large chamber and is prevented from escaping owing to the fact that the upper piston 119 in its upper position, as shown in Figure 3, masks the outlet port 126.

During the running of the locomotive with the throttle open, therefore, the parts will remain in this upper position and the communication between the saturated steam chamber 101 and the passage 112 will be kept closed by the solid portion 115 of the stem 103. Oil from the main reservoir 71 will, however, be permitted to enter the hollow valve stem 103 and descend through the choke ports 118 and into the steam chest and cylinder of the engine due to its mixing with the steam from the throttle.

As soon as the throttle is closed and the locomotive begins to drift, the steam chest pressure will immediately fall under piston 110 and the accumulated pressure in the

dome or upper chamber 122 will force the pistons downwardly to the position shown in Figure 2 thereby establishing communication between the saturated steam chamber 101, which is always in communication with steam at boiler pressure, and the passage 112 thus furnishing steam to the moving parts in the valve chests and cylinder and breaking the vacuum and moistening these parts. Moreover this boiler steam passing the choke head 117 will pick up the oil dropping from the small ports 118 and carry this oil into the moving parts of the locomotive to effectually lubricate the same. When the parts are in the lower position, the upper piston 119 exposes the port 126 so that the accumulated pressure in the upper chamber may escape to the atmosphere.

As the locomotive is slowing to a stop, there is more steam in the locomotive cylinders than the pistons can take care of and consequently a back pressure occurs which gets beneath the lower piston 110 driving the parts upwardly again to the position shown in Figure 3.

This is assisted by the saturated steam pressure beneath the larger area of the upper piston 119. This saturated steam pressure beneath the piston 119 will also hold the parts in the raised position after the locomotive stops and the pressure beneath the lower piston 110 is evacuated.

The oil cup 133 holds but a small quantity of lubricant as compared with the size of the steam chest and cylinders and any accumulation of oil resulting from the dripping from the cup during standing of the locomotive will readily be taken up by the large steam chests and cylinders of the locomotive. The cup 133 provides an auxiliary lubricant supply which is brought into use in case of accident to the main lubricator 71. Preferably the valve 135 of the auxiliary lubricator will be normally adjusted so that only a small quantity of the auxiliary body of lubricant is allowed to escape, the lubrication of the parts being chiefly taken care of by the main lubricant 71. In case of emergency, however, the valve 135 may be opened to a greater extent so as to furnish sufficient lubricant from the auxiliary cup to take care of the entire lubrication of the parts.

The device 71 is a three-feed lubricator used on all locomotives to deliver oil by drops to the steam chest and cylinders of the locomotive. Instead of connecting this lubricator 71 with the steam supply pipe, as is done on all locomotives, in this case, it is connected to the locomotive parts through the port 106 and stem 103. The lubricator operates in the usual way and supplies lubricant at all times, during the running of the locomotive and during short stops. When a prolonged stop is made the engineer

closes the lubricator 71 in the cab. The needle valve 135 may be closed at terminals, if desired, but the quantity of oil is only intended for one trip.

6 The oil in lubricator 71 is under 200 pounds pressure which forces the oil out through the ports 118 in the cap 117 commonly known as a choke. The oil and steam passing through the small ports 118 atomizes and sprays the steam chest and cylinders of the locomotive.

10 The auxiliary lubricator 133 provides oil in small quantities to the stem 103 when the main lubricator 71 is shut off by the engineer.

15 What is claimed:—

An attachment for locomotives comprising a casing having a chamber in communication with a source of steam supply and cylinders communicating at their inner portions with the chamber and at their outer portions with the steam chest pressure, pistons in said cylinders, means to trap the accumulated steam chest pressure on the outer

20 25 face of one of the pistons, the cylinder of said last mentioned piston having means opened in one position of the piston therein for evacuating the accumulated pressure, said casing having a passage in communica-

cation with the locomotive steam chest and 30 with said chamber, a barrel extending through said chamber, a lubricator connecting with the interior of the barrel, a hollow stem connecting said pistons and slidably through said barrel, said stem having a cut 35 out portion to place the chamber in communication with said passage in one position of the stem and said stem having a further cut out portion and ports connecting the last mentioned cut out portion with the 40 interior of the stem for supplying lubricant to the interior of the stem in all positions of the stem, a choke carried by said stem and in communication with the interior thereof, said choke having small passages 45 for the discharge of oil, said choke extending into said passage, and an auxiliary lubricator supported from and movable with said stem and having an equalizing by-pass communicating with the upper and lower 50 portions of the column of lubricant therein, and means to regulate the supply from said auxiliary lubricator.

In testimony whereof we affix our signatures.

CHARLES STERN.
RICHARD W. BRADEN.
